UNITED STATES PATENT OFFICE.

CHARLES ROHLES, OF BUFFALO, NEW YORK.

DESIGN FOR A SMOKING-PIPE.

SPECIFICATION forming part of Design No. 28,089, dated December 28, 1897.

Application filed September 27, 1897. Serial No. 653,264. Term of patent 7 years.

To all whom it may concern:

Be it known that I, CHARLES ROHLES, a citizen of the United States, residing at Buffalo, in the county of Erie and State of New York, have invented and produced a new and original Design for Smoking-Pipes; and I do hereby declare the following to be a full, clear, and exact description of the same, reference being had to the accompanying drawing, forming a part thereof, and which illustrates in perspective a smoking-pipe embodying my design.

As shown in the drawing, the leading feature of such design consists in the pipe shaped substantially like a spigot inverted, with the bowl of the pipe like a keg or barrel.

Referring thereto by letter, S is the stem-piece, which is straight and round with the

exception of a mouthpiece M at one extremity and an enlargement E near the other end. P is the plug, also straight and round and standing at right angles to the stem, which it intersects through said enlargement, the lower end of this plug being shaped like a key K with flat sides, and B is the bowl of the pipe, shaped like a keg or barrel, mounted on the upper end of the plug.

What I claim as new is—

The design for a smoking-pipe, substantially as herein shown and described.

In testimony whereof I affix my signature in presence of two witnesses.

CHARLES ROHLES.
